WINDSHIELD VISOR FOR TRUCKS

Allan W. Lund, 2641 118th Ave. NW,
Minneapolis, Minn. 55433

Filed Dec. 5, 1974, Ser. No. 529,916

Term of patent 14 years

Int. Cl. D12—16

U.S. Cl. D12—191

FIG. 1

FIG. 2

FIG. 3

FIG. 4

FIG. 5

FIG. 6

FIG. 7

FIG. 8

FIG. 9

FIG. 1 is a perspective view of a windshield visor for trucks showing my new design, it being understood that the broken lines are for illustrative purposes only;

FIG. 2 is a plan view thereof;

FIG. 3 is a front elevational view thereof;

FIG. 4 is a side elevational view thereof;

FIG. 5 is a side elevational view thereof opposite to that shown in FIG. 4;

FIG. 6 is a bottom plan view thereof;

FIG. 7 is a rear elevational view thereof;

FIG. 8 is a vertical sectional view taken substantially along line 8-8 of FIG. 7; and

FIG. 9 is a vertical sectional view taken substantially along line 9-9 of FIG. 7.

I claim:

The ornamental design for a windshield visor for trucks, as shown.
